UNITED STATES PATENT OFFICE.

VICTOR EMANUEL EXTROM, OF FULDA, MINNESOTA.

WINDING DEVICE.

1,419,832.

Specification of Letters Patent. Patented June 13, 1922.

Application filed October 19, 1920. Serial No. 417,935.

To all whom it may concern:

Be it known that I, VICTOR E. EXTROM, a citizen of the United States, and resident of Fulda, in the county of Murray and State of Minnesota, have invented a new and Improved Winding Device, of which the following is a full, clear, and exact description.

My invention relates to a motor, and more particularly to a fixture of this nature, which 10 is adapted for use in connection with winding spring motors, such as are used with clocks, but not necessarily limited to this adaption.

I aim to provide a winding device which 15 shall be electrically operated, and which motor shall at all times insure a tensioning of the spring of a mechanical motor, upon the same becoming unwound, and a cessation of said tensioning function upon the spring 20 having been tensioned to a predetermined point.

This adaption is merely taken by way of example, as my improved construction might readily be adapted for a number of 25 other different uses than that of tensioning the spring of a spring motor, although as aforesaid, this is particularly adapted for this use.

A further object of my invention is the 30 construction of a device of this nature, which shall be entirely automatic, and require a minimum of surveillance, and in which the parts shall be simple, and hence economical to manufacture, and positive in operation.

Reference is had to the attached sheet of 35 drawings as illustrating a practical embodiment of my invention, and in which—

Figure 1 is a front view of a device of the 40 nature specified, constructed in accordance with my invention.

Figure 2 is a side view thereof,

Figure 3 is a partly fragmentary face view 45 of the construction of a mechanical motor, and showing certain details of my invention as associated therewith.

Figure 4 is a sectional side view taken of certain parts of my improved motor, and the spring motor which is shown associated therewith, and

50 Figure 5 illustrates a detail of construction of my motor.

In these views the reference numeral 10 indicates the supporting walls, which may form a part of a housing adapted to contain 55 mechanism, such as for instance a train of

clock gears, which are driven by a gear wheel 12, mounted upon a rotatable shaft 13, extending beyond the housing.

It is now to be noted that the shaft 13 has a disk or other suitable element 14 keyed to 60 the same, as has been indicated by the reference numeral 15. Thus, upon the disk 14 being rotated, a rotation will be imparted to the shaft 13. A pin, or other suitable outwardly extending element 16 is secured to 65 the disk 14, and adjacent the outer edge of the same, and it will be seen that in the embodiment illustrated, that one end of a spring 17 may be secured to this pin, the opposite end of said spring being affixed to a 70 sleeve, or a collar 18, which latter is freely rotatable upon the shaft 13.

Assuming now that the collar 18 is held 75 against rotation, and that the coils of the spring 17 have had a certain tension imparted to them, it will be understood that this tensioning will result in a force being exerted, upon the pin 16, resulting, as aforesaid in a rotation of the disk, shaft and gear wheel, or other element 12.

To now provide means, which will serve to prevent a rotation of the collar 18, it will be seen that I have utilized a second disk, or other suitable element 19, which latter is affixed to the collar 18, and preferably adjacent the outer end of the same.

This latter disk is conveniently formed with an annular series of ratchet teeth 20, in its outer edge, which teeth are adapted to be engaged with a pawl 21, to prevent in the 90 form shown, any clockwise motion on the part of the disk 19 whereby any rotation of the collar 18 is prevented.

To effect the tensioning of the springs 17, I rotate in the device illustrated, a disk 19, 95 in an anti-clockwise direction. To automatically effect this, I conveniently affix a solenoid 22 to the supporting walls 10, and rotatably mount as at 23, an armature 24 preferably of the type illustrated in Figure 5, 100 which includes a U shaped body portion, and which armature is adapted to co-act with the solenoid in a manner hereinafter more fully specified.

A spring pressed dog 25 is secured to the 105 armature 24, and engages the teeth 20 of the disk 19. Obviously upon the armature being oscillated around its point of support, 23, it will be seen that the pawl 25 will engage one of the teeth 20, and upon the rock- 110

ing motion being continued, will serve to move the teeth which it has engaged, a certain distance in an anti-clockwise direction. This advance of the disk 19 will be retained 5 by the pawl 21, and a rocking in an opposite direction on the part of the armature 24 will cause the pawl 25 to override one or more teeth 20, before it reaches the end of its stroke, subsequent to which the direction of 10 movement of the armature will be reversed, to again feed the disk in an anti-clockwise direction.

To effect an oscillation of the armature 24, a suitable source of energy (not shown) connects with the terminals 26 and 29, one of the 15 terminals being connected to the windings of the solenoid 22, a second terminal being connected to an adjustable contact pin 27. A contact member 28, bears with one of its 20 ends against the outer end of the pin 27, its opposite end being secured to the armature 24 from which it is suitably insulated, as has been indicated by the reference numeral 29. A lead wire 30, extends from the contact 25 member 28, and affords electrical connection with the windings of the solenoid 22, thus completing the circuit. The completion of 30 this circuit will, as may readily be appreciated, effect an attraction of the armature to the solenoid, causing the same to rock to a position at which it overlies the solenoid, thus effecting a retraction of the pawl 25 in the manner specified. Obviously, the contact 35 member 28 will move with the armature 24, and it will be appreciated, that although the circuit will be completed, and an attraction of the armature effected in the position of the parts illustrated in Figure 1, that upon this attraction taking place, that the circuit 40 will be broken, incident to the contact member 28 moving out of engagement with the contact pin 27.

To return the parts to their normal position, that is, the position indicated in full 45 lines in Figure 1, a spring strip 31 will be bowed upon an attraction of the armature being effected, and will tend to throw the armature back to its normal position, which action will be permitted upon the armature 50 rocking in the structure illustrated in the drawings, in an anti-clockwise direction, thus breaking, as aforesaid, the contact between the elements 27 and 28.

Thus, an oscillation of the armature 24 55 will be produced, which will result in a rotation of the disk 19, and a tensioning of the springs 17. To now provide a medium which will regulate the amount of unwinding, and retensioning of the convolutions of 60 the spring 17; I conveniently mount a third disk 33, upon the collar 18, it being noted that this latter disk is freely rotatable upon this member.

A pin 34 is secured to this disk, and it is 65 to be noted that this pin or obstruction is

in line with the pin 16 of the disk 14, and the pin 35 is affixed to the rear face of the disk 19.

It is to be further noted, that a throw lever 70 conveniently in the form of a bell crank 36 is pivotally secured to one of the supporting walls 10, one of its ends lying adjacent the periphery of the disk 33, its opposite arm being in line adjacent the contact member 28. 75

Also the disk 33, has formed in its periphery, a plurality of inclined shoulders 37, which may be brought to bear against one arm of the bell crank 36. Now assuming that the spring 17 is to be wound, the parts 80 being in the position indicated in Figures 1 and 2, it will be understood that the disk 19 will be actuated in the manner specified, to tension the spring 17.

The disk 19, carrying the pin 35, will 85 eventually rotate the disk 33, for the reason that this pin will engage the pin 34 of the latter disk. The rotation of the disk 33 will result in one of the shoulders 37 contacting, after the disk has moved to a certain distance, with one arm of the bell crank 90 lever 36, thus rocking the same.

When this occurs, the second arm of the bell crank lever 36 will bear against the contact member 28 thus moving the same out of 95 contact with the pin 27 and breaking the circuit, obviously resulting in a cessation of the winding operation.

The spring will now unwind carrying the 100 disk 14 and pin 16 with it. Upon the latter moving to a point adjacent the pin 34 of the disk 33, this member will be moved, consequently moving the associated disk, which will result in the shoulder being moved 105 passed the bell crank 36, thus permitting the contact member 28 to again bear against the pin 27, completing the circuit.

Thus I have provided a motor, more particularly adapted to use in connection with a spring motor, and for tensioning the spring 110 of the latter, but not necessarily limited to this particular use.

This motor, as will readily be appreciated, is extremely simple in construction and positive in operation, so as to require a minimum of expenditure for the original oscillation as well as subsequent upkeep.

It will also be understood that obviously numerous modifications of structure might readily be resorted to without in the least departing from the spirit of my invention which I claim as—

1. A motor including in combination with a shaft and spring having one of its ends attached to said shaft to effect a rotation 125 thereof, of a collar rotatably encircling said shaft and having the opposite end of said spring connected thereto, a disk secured to said collar, a plurality of teeth forming a part of said disk and being arranged at 130

- substantially diametrically opposite points in the periphery thereof, a secondary disk secured to said collar, teeth forming said secondary disk, a pawl adapted to engage 5 said latter teeth, means for effecting a projection and retraction of said pawl to rotate said disk and collar, and means adapted to be engaged by the teeth of the first named disk for causing a cessation of operation of 10 said pawl.
2. A motor including in combination with a shaft and spring, said spring having one of its ends connected to said shaft, of a collar rotatably encircling said shaft the 15 opposite end of said spring being connected to said collar, a disk secured to said collar, a secondary disk also attached to the same, a solenoid, an armature, one of said elements being movable, a pawl connected to 20 said movable element and adapted to engage teeth formed in said last named disk, a contact member, a contact pin adapted to be engaged by the outer end of said member, said member being attached to said movable 25 element and in circuit with said solenoid whereby to cause an attraction of said armature by said solenoid, a spring also attached to said movable member for returning the same to its normal position when the 30 circuit is broken, and means carried by one of said disks for engaging the second arm of said bell crank to move said member out of engagement with said pin.
3. A motor including in combination with a shaft and spring, said spring having one of its ends connected to said shaft, of a collar rotatably encircling said shaft the 35 opposite end of said spring being connected to said collar, a disk secured to said collar, a secondary disk also attached to the same, a solenoid, an armature, one of said elements being movable, a pawl connected to 40 said movable element and adapted to engage teeth formed in said last named disk, a contact member, a contact pin adapted to be engaged by the outer end of said member, said member being attached to said movable 45 element and in circuit with said solenoid whereby to cause an attraction of said armature by said solenoid, a spring also attached to said movable member for returning the same to its normal position when the circuit is broken, and means adapted to 50 be operated by one of said disks for moving said member out of engagement with said pin when said collar has been rotated to a predetermined extent.
4. A motor including in combination with a shaft and spring, said spring having one of its ends connected to said shaft, of a collar rotatably encircling said shaft the 55 opposite end of said spring being connected to said collar, a disk secured to said collar, a secondary disk also attached to the same, a solenoid, an armature, one of said elements being movable, a pawl connected to 60 said movable element and adapted to engage teeth formed in said last named disk, a contact member, a contact pin adapted to be engaged by the outer end of said member, said member being attached to said movable 65 element and in circuit with said solenoid whereby to cause an attraction of said armature by said solenoid, a spring also attached to said movable member for returning the same to its normal position when the circuit is broken, the first named disk being also formed with teeth, a bell crank having one of its arms lying adjacent said 70 75 80 85 90 95 100 105 110 115 120 125 130
5. A motor including in combination with a shaft and spring, said spring having one of its ends connected to said shaft, of a collar rotatably encircling said shaft the opposite end of said spring being connected to said collar, a disk secured to said collar, a secondary disk also attached to the same, a solenoid, an armature, one of said elements being movable, a pawl connected to said movable element and adapted to engage teeth formed in said last named disk, a contact member, a contact pin adapted to be engaged by the outer end of said member, said member being attached to said movable element and in circuit with said solenoid whereby to cause an attraction of said armature by said solenoid, a spring also attached to said movable member for returning the same to its normal position when the circuit is broken, a bell crank having one of its arms lying adjacent said member, and means carried by one of said disks for engaging the second arm of said bell crank to move said member out of engagement with said pin.
6. A motor including in combination with a shaft and spring, said spring having one of its ends connected to said shaft, of a collar rotatably encircling said shaft the opposite end of said spring being connected to said collar, a disk secured to said collar, a secondary disk also attached to the same, a solenoid, an armature, one of said elements being movable, a pawl connected to said movable element and adapted to engage teeth formed in said last named disk, a contact member, a contact pin adapted to be engaged by the outer end of said member, said member being attached to said movable element and in circuit with said solenoid whereby to cause an attraction of said armature by said solenoid, a spring also attached to said movable member for returning the same to its normal position when the circuit is broken, the first named disk being also formed with teeth, a bell crank having one of its arms lying adjacent said member.

- member its opposite arm extending into the path of travel of the last named teeth whereby upon said disk having been rotated to a predetermined extent one of said 5 teeth will bear against the arm of the bell crank to cause the second arm of the same to move into contact with said member, to in turn move said member out of engagement with said pin.
10. 7. In a motor, including in combination with a shaft, and a spring for driving said shaft having one of its ends secured to the sleeve of a collar rotatably mounted upon said shaft, a disk secured to said collar, said 15 disk being formed with ratchet teeth, together with an armature, and a solenoid, means for permitting a flow of current to effect an attraction of said armature with respect to said solenoid, means for returning 20 said armature to its normal position, and a pawl secured to said armature and adapted to engage the ratchet teeth of said disk.
8. A motor, including in combination with a shaft, and a spring for driving said shaft having one of its ends secured to the sleeve 25 of a collar rotatably mounted upon said shaft, a disk secured to said collar, said disk being formed with ratchet teeth together with an armature, and a solenoid, a contact 30 member secured to said armature, a resilient strip also secured to said armature, a contact pin, said contact member being adapted to bear against said contact pin, a bearing member, said resilient strip being adapted 35 to engage said bearing member, said solenoid being arranged in circuit and continuing through the contact member and pin, a pawl secured to said armature and adapted to engage the teeth of said disk, said armature 40 moving upon the aforespecified circuit being closed, to a point adjacent said solenoid, whereby said contact member carried by said armature will move out of contact with said pin to break the circuit, said resilient strip returning said armature subsequently to its normal position, whereby to 45 move said disk and collar.
9. A motor, including in combination with a shaft, and a spring for driving said shaft having one of its ends secured to the sleeve 50 of a collar rotatably mounted upon said shaft, a disk secured to said collar, said disk being formed with ratchet teeth together with an armature, and a solenoid, a contact 55 member secured to said armature, a resilient strip also secured to said armature, a contact pin, said contact member being adapted to bear against said contact pin, a bearing member, said resilient strip being adapted to 60 engage said bearing member, said solenoid being arranged in circuit and continuing through the contact member and pin, a pawl secured to said armature and adapted to engage the teeth of said disk, said armature moving upon the aforespecified circuit being closed, to a point adjacent said solenoid, whereby said contact member carried by said armature will move out of contact with said pin to break the circuit, said resilient strip returning said armature subsequently to its normal position, whereby to move said disk and collar.
10. A motor, including in combination with a shaft and a spring for driving said shaft having one of its ends secured to the sleeve of a collar rotatably mounted upon said shaft, a disk secured to said collar, said disk being formed with ratchet teeth together with an armature, and a solenoid, a contact member secured to said armature, a resilient strip also secured to said armature, a contact pin, said contact member being adapted to bear against said contact pin, a bearing member, said resilient strip being adapted to engage said bearing member, said solenoid being arranged in circuit and continuing through the contact member and pin, a pawl secured to said armature and adapted to engage the teeth of said disk, said armature moving upon the aforespecified circuit being closed, to a point adjacent said solenoid, whereby said contact member carried by said armature will move out of contact with said pin to break the circuit, said resilient strip returning said armature subsequently to its normal position, whereby to move said disk and collar, and means operated by said disk for breaking the circuit upon the spring being tensioned to a predetermined point.
11. A motor, including a rotatable shaft, a disk secured to said shaft, a spring, a pin secured to said disk and one end of the spring, a collar rotatably mounted upon said shaft, the opposite end of said spring being secured to said collar, a disk secured to said collar, a third disk rotatably mounted upon said collar, pins secured to said last named disks, and in line with each other and the first named disk, and means operated by said last named disk for effecting a rotation of the second disk, and consequential tensioning of said spring.

VICTOR EMANUEL EXTROM.
